A. Lawton,

Raising Coal.

NO. 96,927.

Patented Nov. 10, 1869.

United States Patent Office.

ALFRED LAWTON, OF PHILADELPHIA, PENNSYLVANIA.

Letters Patent No. 96,927, dated November 16, 1869.

IMPROVEMENT IN RAISING AND MOVING COAL, &c.

The Schedule referred to in these Letters Patent and making part of the same.

I, ALFRED LAWTON, of Philadelphia, county of Philadelphia, State of Pennsylvania, have invented certain Improvements on Moving and Raising Coal and other granular material, of which the following is a specification.

Nature and Object of the Invention.

My invention consists in certain improvements, fully described hereafter, in the method of moving and raising coal and other granular material, for which Letters Patent were granted to me on the 13th day of July, 1869, the improvements being such that although the coal or other material will of itself pass into the car or other vessel in which it is to be raised, as in my patented invention, yet it is not necessary, as in the latter, that the mass of coal, &c., should surround or be in close proximity to the elevating-shaft, or its equivalent; in fact the main object of my present invention is to avoid the necessity of surrounding the shaft and to enable masses of granular material to be conveyed from points more or less remote to the said shaft, or its equivalent, and to be raised in the latter, without any of the usual tedious and costly labor which would be demanded in removing the same material by means of shovels and wheelbarrows.

Description of the Accompanying Drawing.

Figure 1 is a vertical section of apparatus, which may be used in carrying out my invention;

Figure 2, a plan view of the same;

Figure 3, a vertical section on the line 1-2, fig. 1;

Figure 4, a sectional plan on the line 3-4, fig. 1; and

Figure 5, a perspective view of the upper portion of the elevating-shaft.

General Description.

A represents a platform, which may be either wholly or in part of open trestle work, and on a level with or at such convenient height above the surface of the ground as will enable cars to be conducted on to or from the said platform upon tracks a.

Beneath this platform or trestle work is a second platform, B, upon which is deposited the coal or other material to be moved and raised, as hereafter explained, the latter platform being usually on a level, or thereabouts, with the surface of the ground, although this is not important.

Extending under the entire platform B is a space or chamber, C, the bottom D of which should be at a sufficient distance beneath the platform to permit the passage to all parts of the said chamber of a small car or other conveying vessel F, the wheels of which run upon tracks b b b, laid upon the bottom D of the chamber, said tracks merging into a single track, V, at a point beneath a shaft or elevator, H.

A number of openings, i, are formed in the platform B, at points directly above the tracks b, and each of these openings is, in the present instance, furnished on the under side of the platform with a sliding door, j; but it should be understood that these doors may be level with or on the top of the platform, and that they may be hinged or arranged in any manner which will best answer the purpose.

It is essential, however, that the openings or traps i should be somewhat less in size than the top of the car or conveyer F.

The shaft or elevator H, before referred to, is built of any suitable material, and to any required height, and may be continuous and entirely enclosed, as shown in fig. 1; or it may be constructed in two sections, the lowermost extending between the platforms A and B, and being entirely closed, while the uppermost section may be nothing more than a light open frame-work, which can, if desired, be mounted upon wheels, arranged to run upon a track, k, as seen in figs. 2 and 5, this latter arrangement, when the apparatus is constructed upon so extended a scale as to require a number of shafts, effecting considerable economy, as the lower section only need be permanent, while the upper movable section can be shifted from point to point, and fitted over any of the lower sections, as it is required for use.

It is intended that the shaft or elevating-tube shall be furnished with hoisting-tackle, operated by any suitable gearing, under the control of an attendant, and that this tackle shall be employed to raise or lower the car or conveyer F, which is arranged to slide in the shaft.

Although I prefer that the bottom of the shaft should not be sunk below the platform of deposit B, as described in my aforesaid patented invention, for the reason that the chamber C takes the place of the sunken portion of the shaft, and is in fact nothing more than an extension of the same, yet the shaft or a portion of it may, if desired, be extended below the platform without departing from my invention, but this will only be rendered necessary when the shaft takes the form of an inclined plane, having a track upon its lower side to receive the wheels of the car F.

It should be understood, before proceeding further, that the conveyer F may consist of a car, such as shown in the drawing, or of a bucket adapted to the interior of the shaft, and arranged to be conveyed about the chamber upon a wheeled truck, or of any other convenient form and construction that circumstances may suggest.

It should also be understood that in some cases the platform A can be dispensed with, and the tracks laid directly upon the platform B, but I prefer in most cases that the several platforms should be arranged as shown in the drawing.

In using the above-described apparatus, the mass of coal or other granular material to be removed and elevated is first deposited upon the platform B by cars running upon the tracks *a* of the upper platform A. The car or conveyer F is then moved upon one of the tracks *b* to a point beneath one of the openings *i*, the door *j* of which is so moved as to uncover the whole or a portion of the said opening, when coal from the mass upon the platform will of itself rush down into the car until the latter is filled, the door *j* being then closed.

The loaded car is next run upon the track *b* to a point directly beneath the lower open end of the shaft, and is raised to the top of the latter by means of the aforementioned gearing under the control of an attendant, the car after reaching the top of the shaft being tilted, or its contents otherwise disposed of.

The car being lowered is again run upon one of the tracks *b* to a point beneath any one of the openings *i*, whether adjacent to or remote from the shaft, and is filled as before, and so on until the desired quantity of coal or other material has been moved and raised.

It will be observed from the above that the main feature of my patented invention, namely, so arranging the shaft, or rather the hoisting-vessel, in respect to the mass of coal or other material to be raised, that the latter will of itself pass into the said vessel, is adhered to in the present instance.

In my former invention, however, it was necessary to sink the shaft below the surface of the ground or platform, in order to permit the hoisting-vessel to be lowered to a sufficient extent, and also to wholly or in part surround the shaft with the material to be elevated, this necessarily confining the operation of the apparatus to a comparatively limited space.

In my present invention, however, which is merely an extension of the same principle, it is not necessary that the mass should surround the shaft, or even that it should be in close proximity to the same, the only requirement being the providing of sufficient space beneath the shaft and beneath the material to be elevated, as to permit the passage of the hoisting-vessel or car, as before described.

The importance of my invention will be understood if we suppose it to be erected at any place where large masses of coal are deposited to be removed from time to time, as, for instance, at the coal-wharves or depot of a railroad or canal.

In consequence of the tedious and costly labor demanded in piling up and removing these masses of coal by the aid of shovels and wheelbarrows alone, it has been customary, in order to economize this labor, to deposit the masses as close as possible to the point

of shipment, so that the wharves and depots, in order to sustain the great weight to which they are subjected, must necessarily be massive and expensive structures; and it oftentimes happens that valuable space at the ends of the wharves is entirely occupied by the masses of coal awaiting shipment, and which cannot economically be placed elsewhere.

All of these difficulties are at once overcome by the use of my invention, for the coal which is not to be shipped immediately can be deposited from the cars as it arrives directly upon a platform, placed at any convenient point at the rear of the wharves or depot, from which platform it can be raised in the manner before described, in the quantities, and at the times required. The wharves, also, not having to sustain the heavy masses of coal, can be light and inexpensive structures, of sufficient strength only to sustain the weight of the tracks, and of the cars in which the coal is carried to the points of shipment.

Claims.

1. The moving and raising of coal or other granular material by means of a car or suitable vessel, arranged to move in a chamber which extends beneath the platform upon which is deposited the coal or other material to be raised, and beneath a shaft, or its equivalent, so that the said material will of itself pass into the vessel, and so that the latter when filled may be raised in the said shaft, or its equivalent, all substantially as herein set forth.

2. In combination with the said chamber extending beneath the platform of deposit, the openings *i* in the latter, each furnished with a suitable door, *j*.

3. The arrangement, at the bottom of the chamber C, of the tracks *b* and *b'*, or any equivalent arrangement of tracks, whereby the car or conveyer F can be conducted from the elevating-shaft to any of the openings *i* in the platform of deposit, or *vice versa*.

4. An elevating-shaft, consisting of a lower permanent portion, and of an upper movable portion, substantially as described, and as represented in figs. 2 and 5 of the drawing.

5. The arrangement, substantially as herein described, in respect to the chamber C and elevating-shaft, of the platforms A and B.

In testimony whereof, I have signed my name to this specification, in the presence of two subscribing witnesses.

ALFRED LAWTON.
